CLAIM

The ornamental design for a media player device as shown and described.

DESCRIPTION

FIG. 1 is a front elevation view of a media player device.

FIG. 2 is rear elevation view thereof.

FIG. 3 is a top plan view thereof.

FIG. 4 is a bottom plan view thereof.

FIG. 5 is a left side view thereof.

FIG. 6 is a right side view thereof.

FIG. 7 is a perspective view thereof.

FIG. 8 is a second perspective view thereof; and,

FIG. 9 is a third perspective view thereof.

The features shown in dash-dot broken lines do not form part of the claimed design.

1 Claim, 9 Drawing Sheets
